(57) **CLAIM**

The ornamental design for a tension curtain rod support, as shown and described.

DESCRIPTION

FIG. 1 is a front view of a tension curtain rod support showing my new design;

FIG. 2 is a rear view of the tension curtain rod support; FIG. 3 is a left side view of the tension curtain rod support; FIG. 4 is a right side view of the tension curtain rod support; FIG. 5 is a top view of the tension curtain rod support; and, FIG. 6 is a bottom view of the tension curtain rod support. The broken lines in the drawing depict environmental subject matter only and form no part of the claimed design.
